UNITED STATES PATENT OFFICE.

JOHN K. OLSEN, OF CHICAGO, ILLINOIS, ASSIGNOR TO STEWART-WARNER SPEEDOMETER CORPORATION, OF CHICAGO, ILLINOIS, A CORPORATION OF VIRGINIA.

MAGNETIC SPEEDOMETER.

Application filed September 1, 1922. Serial No. 585,628.

This invention relates to speedometers of the magnetic type. Its purpose is to provide a magnetic speedometer in which a rotating magnet of less weight than heretofore commonly employed shall exert a stronger magnetic drag upon the drag element, and in which the construction shall be more compact and economical than hitherto commonly employed, and by reason of the superior 5 mounting or the method of mounting, the rotating parts shall be adapted to be driven at a higher speed than previous instruments of this class, further increasing the magnetic drag and permitting the use of a stronger 10 biasing spring, and therefore rendering the instrument less susceptible to disturbance from exterior jarring or other causes which tend to interfere with the accuracy of the 15 mileage indications. It consists in the features and elements of construction shown 20 and described as indicated in the claims.

In the drawings:—

Figure 1 is a front or face view of the instrument as a whole, same being a combined magnetic speedometer and odometer. 25

Figure 2 is a front elevation of the same with the face plate and the odometer removed showing only the speedometer mechanism in the casing.

Figure 3 is a side view of the mechanism and support therefor shown in Figure 2, the casing being removed.

Figure 4 is a section in part at the line, 4—4, on Fig. 2 and on Fig. 7.

Figure 5 is a section through the casing at the line 5—5, on Figure 4, showing the speedometer mechanism and support in top plan view.

Figure 6 is a detail section at the line 6—6 on Figure 5.

Figure 7 is a section at the line, 7—7, on Figure 4.

Figure 8 is a section at the line, 8—8, on Figure 2 and Figure 7.

The structure shown in the drawings comprises a sheet metal casing, A, which is of sheet metal stamping, and is in general in cup form, that is, cylindrical with a bottom or back web. Within this casing there is 45 mounted the speedometer support, B, which is preferably a unitary die-casting. It is adapted to have secured to it the support for odometer mechanism not shown, which when mounted occupies the space, C, (see 50 Figure 3) in front of the back plate and

below the horizontal web of the speedometer support hereinafter more particularly described. The support, B, comprises a vertical back web, B¹, which has a flange, b¹, for fitting within the cylindrical casing; and a horizontal or par-axial web, B¹⁰, a little above the horizontal diameter of the cylindrical outline of the casing and flange, b¹. The back web, B¹, has the journal bearing boss, B¹¹, for the inleading power shaft D. 60 The horizontal web, B¹⁰, has a journal bearing boss, B¹³, for the vertical shaft of the speedometer magnet and a bearing for that shaft is provided in the forward end of a boss, B¹⁴, which projects from, and is an extension of the journal bearing boss, B¹¹, as seen most clearly in Figure 4. The magnet shaft, E, is tubular and has intermediate 65 its said bearings a spiral gear, F, which is driven by a spiral gear, D¹, on the in-leading power shaft, D. The magnet, G, is of the "split-ring" type. It is mounted upon the upper end of the shaft, E, being carried by a non-magnetic sheet metal stamping, G¹, which constitutes an annular cup for the 70 ring magnet, said cup being telescoped onto a grease cup, G², which is in turn telescoped onto the upper end of the shaft, E, as seen in Figure 4. The grease cup, G², has ports, g², at the inner circumference of its bottom 75 by which the lubricant is delivered to the upper bearing of the shaft, E, which is obtained in a bearing bushing, F¹, forced into the journal bearing boss, B¹³. A grease cavity, f¹, is provided in the journal bearing 80 between the ends thereof which serves to hold a limited quantity of lubricant which reaches it from the cup, G². The lubricant which may flow down along the shaft, E, from said lubricant pocket, f¹, reaching the 85 spiral gear, F, is centrifugally delivered from the upper side of said gear to the mesh of said gear with its driving gear, D¹. Lubricant from the grease cup, G², flowing 90 by the course indicated will reach the intermeshing gears, F and D, and then passing along the shaft, E, reaches the lower bearing thereof in the bushing sleeve, F², which is pinned into the forward extension, B¹⁴, 95 above mentioned, of the journal bearing boss, B¹¹, said bushing having at its rear side an aperture as seen at f² registering with the passage, b¹¹, for admitting the lubricant. 100

The magnet, G, is desirably thin relatively to its width; and the diameter of its open 110

center is small relatively to its outer diameter; that is, the magnet is a relatively flat ring so that it presents laterally to the field plate and the drag element a relatively large area from which the flux to be cut by the drag element may emanate. But for giving the maximum drag efficiency to the magnet it is desirable that the flux lines cut by the drag element shall be, in as large a proportion as possible, near the circumference of the magnet, so as to operate with maximum radius of leverage upon the drag element. For this purpose in the first place the magnet gap is widened taperingly toward the center as seen clearly in Figure 5, said gap being quite narrow for a short portion, g , commencing at the outer circumference and then widened taperingly for the remainder of the width of the magnet ring as seen at g^1 . The effect of this form of gap is that the lines of flux passing from pole to pole tend to pass at the point of least reluctance which is at the narrow portion of the gap, and the flux is therefore concentrated at this portion of the magnet to the limit of saturation, being correspondingly diminished at the inner portion where the gap is wider. Due to the saturation at the outer portion of the magnet there are more stray lines at the outer portion which may be deflected by the field plate so as to be cut by the drag element; and being thus cut at the outer circumference of the magnet the flux operates with the advantage of maximum radius leverage for drag effect. Further to increase the drag effect by causing the deflected flux to be cut by as large a cross-sectional area as possible of the drag element, the field plate, H , comprising a trans-axial web and mounted as hereinafter described has a marginal annulus, H^2 , offset from the plane of the remainder parallel thereto, forming between the main portion of the web and said annulus, a par-axial annular portion H^1 connecting said offset annulus with the main central area of the plate, said offset annulus and said par-axial connecting annulus being dimensioned for positioning the offset annulus, H^2 , encompassing the magnet at a sufficient distance radially therefrom to admit between the magnet and said encompassing portion an annular par-axial portion, K^1 , of the drag element, K , which is produced as hereinafter more particularly described. The field plate, H , is carried in its position parallel to the upper face of the magnet by a plurality of brackets,—four being shown,— L^1 , L^2 , L^3 and L^4 , each made of two laminae, both being non-magnetic and having different coefficients of expansion by heat, that of the outer lamina being the higher, so that the brackets are flexed slightly by changes of temperature, are footed on the horizontal web, B^{10} , of the

support, B , as seen most clearly in Figure 5, and extend up outside the drag element, K , and thence project inward radially overhanging the field plate; and said field plate is suspended from said overhanging bracket arms by bolts, l^1 , which project from the field plate, and provided with securing nuts, l^2 , above the bracket arms, springs, l^3 , being interposed between the field plate and the overhanging ends of the bracket arms, so that by slackening or screwing on the nuts more or less the field plate may be lowered toward or lifted from the magnet. The purpose of this feature of the construction, regardless of the adjustability indicated, is that since the attraction of the magnet for the field plate tends to spring the bracket arms down, rise of temperature and relaxing of the stiffness of the bracket arms causes the field plate to approach the magnet, and this approach compensates for the diminution of magnetic drag which results from the same rise of temperature.

The drag element is in inverted cup form having its web or bottom secured to the upper end of a spindle, N , which extends down through the hollow magnet shaft, E , and is stepped at its lower end in a bearing jewel, n^1 , carried by a jewel cup, N^1 , screwed through a supporting arm, N^2 , which is bolted onto the under side of the horizontal extension, B^{14} , which at its forward end carries the journal lower bearing of the shaft, E , as stated, the jewel cup, N^1 , protruding into the axial cavity of the shaft, E . For the upper bearing of the spindle, N , and for stopping the same upwardly there is provided a bracket, R , footed on the web, B^{10} , intermediate the footing of the two rear brackets, L^1 and L^2 , said bracket, R , extending up past the drag cup, and having an arm, R^1 , projected forward to intersect the axis of the magnet and spindle, N , and provided with a second arm, R^2 , parallel to the arm, R^1 , above the same also intersecting said axis. In the arm, R^1 , an upper bearing is provided for the spindle, N , and the upper end of the spindle is stopped under and against the upper arm, R^2 , all as most clearly seen in Figure 4. The field plate, H , is annular and the drag cup, K , has at the center of its bottom or web an up-struck boss, k^3 , which protrudes through the open center of the field plate. The spindle, N , is secured to the drag cup at the top of this up-struck boss by means of clamping collars, n^4 and n^5 , pressed onto the spindle respectively below and above the top web of said boss, the spindle being reduced in diameter above the seat of the collar to obtain an upper bearing in the bracket arm, R^1 .

The drag cup having its web or bottom secured as described to the spindle comprises in addition a par-axial flange or wall, K^1 , diametered for encompassing the magnet, 130

and having projecting outwardly from it a trans-axial annulus, K^2 , from whose outer circumference a graduated scale flange or skirt, K^3 , depends parallel to the axis. The 5 field plate, H , having the par-axial annulus H^1 , and the trans-axial peripheral flange, H^2 , overhangs and encompasses the trans-axial web and par-axial annulus, K^1 , of the drag cup, and said flange, H^2 , overhangs the 10 annulus, K^2 , of the drag cup, the outer diameter of said flange being substantially the inner diameter of the skirt or outer flange, K^3 , of the drag cup. Upon considering this 15 construction it will be seen that the three elements,—ring magnet, drag element and field plate,—are nested one within the other in the order stated; that is, the magnet being nested in the drag cup and the drag cup nested in the field plate. The purpose and 20 effect of this construction is that the stray lines of flux deflected by the field plate at the outer circumferential portion of the latter comprising the flange, H^2 , and annulus, H^1 , intervening between said flange and the 25 main web, H , are cut by an extended portion of the drag cup in the form resulting from the flexure in opposite directions from the part intermediate such flexures, said form comprising an outer circumferential 30 portion of the web, K , the par-axial annular portion, K^1 , and the peripheral trans-axial flange, K^2 , and thereby a maximum proportion of the lines of the deflected spray flux are cut by the drag cup with the maximum 35 radius; with the effect of obtaining from a magnet of given size and degree of saturation, the maximum drag effect.

For mounting the biasing spring, S , the bracket arm, R^1 , has a laterally extended 40 terminal, R^{10} , and a lug, r^{10} , up-turned therefrom, said lug being apertured for insertion of the outer end of the coiled spring, S , with a wedging pin, r^{12} , for pinning it fast at its outer end. The inner end of the 45 spring is secured to a collet, n^6 , pressed onto the upper end of the spindle, N . The bracket arm, R^{10} , has a forwardly projecting terminal, R^{11} , for stopping the swing of the drag element under the stress of the 50 biasing spring at zero position, a lug, k^4 , being struck up from the hollow boss, k^3 , for that purpose.

It will be observed that, taking advantage of the depth below the plane of the 55 rotating magnet necessary to accommodate the odometer mechanism (not shown), the magnet is given an unusually long vertical shaft having its bearings widely spaced apart. This has the effect of making the 60 magnet steady itself by its own rotation, giving it a spinning top character, and this is the purpose of this feature of the construction.

In the foregoing description and in the 65 following claims, the terms "trans-axial"

and "par-axial" are employed with their etymological meanings, respectively, viz, transverse to the axis, and in the direction of and laterally offset from the axis.

I claim:

1. In a magnetic speedometer comprising a magnet element which is disposed about an axis and mounted for rotation about the same axis, the width of the magnet gap being in a direction circumferential about 75 said axis; a field plate mounted trans-axially of the magnet element having an annular marginal portion offset along the axis from the inner portion of the plate, whereby there is formed encompassing the magnet a par-axial annulus which is encompassed by a trans-axial annulus, and a drag element in cup form with its trans-axial web or bottom interposed between the magnet and the field plate and having its wall consisting of two 80 flange portions with an intervening trans-axial annular web, the lesser-diametered flange encompassing the magnet between the same and the par-axial annulus of the field plate, said intervening annular web being 85 proximate to the peripheral trans-axial flange of the field plate; whereby the flux emanating both from the periphery and the lateral margin of the magnet is concentrated for traversing the drag element at maximum 90 distance from the axis.

2. In a magnetic speedometer in combination with a support a magnet mounted thereon for rotation about an axis, a drag element and a field plate formed for circum-axially encompassing the magnet by the drag element and the drag element by the field plate, bi-metallic brackets symmetrical- 100 ly distributed about the axis and footed on the support radially beyond the drag ele- 105 ment and extending upwardly, and having arms extending inwardly overhanging the field plate, and means for suspending the field plate from the ends of said overhang- 110 ing bracket arms.

3. In a magnetic speedometer in combination with a support, a ring magnet mounted thereon for rotation about its axis, a trans-axial field plate; a drag element in cup form and a spindle by which it is mounted for os- 115 cillation about the axis of the magnet with its web trans-axially interposed between the magnet and the field plate and its flange en- 120 compassing the magnet and depending there- 125 below, the field plate being annular and the drag element having a central up-struck boss which protrudes through the open center of the annular field plate for securing of the drag element to its spindle above the field plate; a bracket of non-magnetic mate- 130 rial footed on the support outside the bracket arm, extending up and having an arm ex- 135 tending in above the field plate substantially in the plane of the top of said up-struck boss, and a biasing spring for the drag ele-

- ment secured at one end to said bracket arm and at the other end to the drag element at a point on its spindle above the boss.
4. In a magnetic speedometer in combination with a support, a ring magnet mounted thereon for rotation about its axis, a transaxial field plate; a drag element in cup form; and a spindle by which it is mounted for oscillation about the axis of the magnet
- 10 with its web trans-axially interposed between the magnet and the field plate, and its flange encompassing the magnet and depending therebelow, the means for carrying the field plate comprising bimetallic brackets footed on the support and having arms extending up therefrom outside the drag element and thence inward over the field plate for terminating thereabove, means for suspending the field plate from said overhanging bracket arms; whereby the direct magnetic pull of the magnet on the field plate tends to put said bracket arms under tension of flexure.
5. In a magnetic speedometer in combination with a support a magnet mounted thereon for rotation about an axis, a drag element and a field plate formed for nesting the magnet in the drag element and a drag element in the field plate, and a casing in which
- 20 all said elements are nested, the field plate having a marginal transaxial annular por-

tion, the drag element having for such nesting a par-axial annulus and a transaxial annulus encompassing it, the parts being dimensioned for locating the transaxial marginal annulus of the field plate adjacent the transaxial annulus of the drag element, the drag element having a flange extending from the periphery of its said transaxial annulus forming for carrying the speed graduations, a skirt flange positioned proximate to the case wall for approximating the reading aperture, whereby the diminution of drag due to the radial offsetting of the skirt flange for approximating the reading aperture is compensated by the co-operation of the transaxial annuli of the field plate and drag member respective.

6. In a magnetic speedometer comprising a ring magnet having an invariable gap mounted for rotation about its axis, a field plate for concentrating the stray flux, a drag element interposed between the magnet and the field plate for cutting the concentrated flux as the magnet rotates, the magnet gap being widened diametrically from a point intermediate the two circumferences to the inner circumference of the magnet.

In testimony whereof, I have hereunto set my hand at Chicago, Illinois, this 22 day of August, 1922.

JOHN K. OLSEN.
